MEANS FOR ATTACHING CLIPS TO
PENS, ETC.

Arthur W. Schoneberger, Cincinnati, Ohio

Application July 28, 1937, Serial No. 156,151

4 Claims. (Cl. 24—11)

This invention relates to clips and more particularly to clips adapted to be used on the caps of fountain pens and the like.

The principal object of my invention is to provide a self-anchoring clip for use on the cap portions of fountain pens and other writing instruments.

Another object of my invention is to provide a self-anchoring clip for use on the cap portions of fountain pens and the like which is adapted to be quickly and economically attached to said cap.

A further object of my invention is to provide a simple device wherein by novel construction, a clip may be attached to a cap without the use of rivets or brads.

With the above and other objects in view, the invention consists in general of certain novel details of construction and combination of parts hereinafter fully described, illustrated in the accompanying drawing, and broadly claimed.

In the accompanying drawing, like characters of reference indicate like parts in the several views, and:

Fig. 1 is a plan view of my invention.

Fig. 2 is a cross section on the line A—A of Fig. 1.

Fig. 3 is a section of a modification of my invention.

Fig. 4 is a section of another modification of my invention.

Fig. 5 is a perspective view of my invention, and

Fig. 6 is a similar view of a modification of my invention.

In the embodiment of my invention as shown in the present drawing, there is provided a clip made of metal or other suitable material, having a convex shaped body portion 1, a tail portion 2, terminating in a ball 3. The edges of the convex body portion are downwardly bent to form downwardly extending flanges 4, the edges of which are outwardly curved to form a U-shaped edge 5, or bent as shown in Figs. 2 and 4 or inwardly bent as shown in Figs. 3, 5, and 6, to form sharp V-shaped edges 5 as shown in Figs. 3, 4, 5, and 6. If desired, the edge 5 may be provided with teeth or serrations 6 to firmly anchor the clip in the slots 7 of the fountain pen cap 8.

In attaching my improved clip to the cap portion of a fountain pen or the like, a plurality of parallel slots 7, are cut or formed in the cap 8, the cap being made of any suitable material such as vulcanized rubber, pyroxalin, or a synthetic resin, such as the product known as "Bakelite". The edges of the body portion, are laterally compressed and the downwardly extending flanges 4

are inserted in the slots 7. The pressure on the body portion is then released and the edges 5 and 6, preferably sharpened, dig into the cap material 8 and securely anchor the clip thereto as shown in Figs. 2, 3, and 4.

If desired, the transverse width of the turned lower ends of the flanges may be slightly in excess of the width of the pockets 7, whereby, upon pressing or forcing the turned lower portion of the flanges against the bottoms of the pockets, 10 the free ends of the flanges, such as 5 in Fig. 2, are caused to turn out slightly and thus securely grip the side walls of the pockets. The walls of the pockets in the body of the cap 8, are preferably parallel, and the free ends 5 of the clip 15 flanges engage oppositely disposed walls of said pockets. By opposed or oppositely disposed pocket walls, is meant that the outermost pocket walls 20 and 21 are used when the free ends of the flanges are turned outward as shown in Figs. 20 2 and 4, whereas the inturned free ends of the clip flanges, shown in Fig. 3, grip the innermost pocket walls 22 and 23. The gripping action is approximately the same in both forms of the invention.

The clip is preferably made of material having inherent spring characteristics, whereby to augment the gripping action of the ends of the flanges.

The foregoing detailed description has been given for clearness of understanding only and no unnecessary limitations should be understood therefrom, but it should be construed as broadly as permissible in view of the prior art.

The arcuate cross sectional contour of the clip body, together with the inherent spring characteristics of the material from which same is made, augments the gripping action of the free ends of the flanges on the walls of the pockets. This gripping contact may be nicely controlled by so spacing the pockets that a slight contracting or expanding of the flanges is required incident to insertion thereof into the pockets, thus placing the body of the clip under tension or strain that may be utilized for maintaining the bite of the flange 45 upon the pocket walls.

What is claimed is:

1. The combination with a body having a pair of spaced pockets, each of which pocket comprises a wall that is substantially parallel with a wall of the other pocket, of a clip comprising a resilient body extending between the pockets and being arcuate in cross section, and flanges carried at opposite ends of and extending from the arcuate portion of the body, the flanges extending 55

into the pockets and gripping means on each of said flanges, comprising retroverte sharp edged portions engaging the said parallel walls and held in gripping contact upon said walls incident to the spring tension of the arcuate portion of said clip, tending to move the gripping means in the directions of the respective parallel walls contacted by said gripping means.

2. The combination with a body having a plurality of spaced pockets each of which pockets comprises a wall susceptible to partial penetration by a sharp object, of a clip comprising a resilient body portion extending across the pockets, and a plurality of spaced flanges, one for each pocket, extending from the body portion of the clip in a substantially common direction of extension, the spacing between said flanges being unlike the spacing between the pockets so as to require flexing of the body portion to enable insertion of the flanges into their respective pockets, and a reversely directed anchor means on each flange, having a sharp edge extending in the general direction of the body portion of the clip and toward those walls of the pockets which bear the force imposed by the flanges under strain as aforesaid.

3. The combination with a body having spaced

pockets, the walls of the pockets being substantially parallel, of a clip comprising a body portion extending between the pockets and having flanges at its opposite sides extending away from the clip body, each flange terminating in an upturned pocket wall engaging free edge bent back from said flange portion towards the body portion of said clip, the horizontal distance from each flange to its free upturned edge being greater than the width of an individual pocket so as to place each flange under tension when introduced into its pocket and so that the upturned edge of each flange is urged into the walls of its pocket upon attempted removal of said flange from said pocket.

4. As a new article of manufacture, a fountain pen clip comprising a body portion and a tail portion, a pair of downwardly projecting parallel prongs continuous with and extending downwardly from opposite sides of said body, the end of each flange terminating in a self-anchoring lip turned back in reverse direction to the general direction of extension of the flange from the clip body, the lateral edge of each lip being serrated and sharpened to facilitate independent anchorage to a support.

ARTHUR W. SCHONEBERGER.
